DESIGN FOR A TOY

Thomas J. Parker, Cincinnati, Ohio, assignor of one-half to L. S. Ausdenmoore, Cincinnati, Ohio

Application August 15, 1944, Serial No. 114,894

Term of patent 3½ years

(Cl. D34—15)

To all whom it may concern:

Be it known that I, Thomas J. Parker, a citizen of the United States, residing at Cincinnati, in the county of Hamilton and State of Ohio, have invented a new, original, and ornamental Design for a Toy, of which the following is a specification, reference being had to the accompanying drawing, forming a part thereof.

Figure 1 is a side elevation of the toy embodying
my new design; and

Figure 2 is a plan view of the same.

I claim:

The ornamental design for a toy, substantially
as shown.

THOMAS J. PARKER.
